UNITED STATES PATENT OFFICE.

DAVID AMBLER, OF IRMA, ALBERTA, CANADA.

GRAIN-PAN SCREEN.

1,223,352.

Specification of Letters Patent. Patented Apr. 24, 1917.

Application filed March 17, 1916. Serial No. 84,948.

To all whom it may concern:

Be it known that I, DAVID AMBLER, a subject of the King of Great Britain, and resident of Irma, in the Province of Alberta, 5 Dominion of Canada, have invented certain new and useful Improvements in Grain-Pan Screens, of which the following is a description.

This invention relates to improvements in 10 grain separators, and particularly applies to the grain pans thereof, and the objects of the invention are to facilitate in separating the tame from the wild grain and also the poorer from the better class of grain, to effectively remove the chaff, to simplify the 15 construction of the mechanism and generally to adapt the several parts to better perform the functions required of them.

With the above objects in view the invention 20 consists essentially of the improved construction particularly described and set forth in the following specification and accompanying drawing forming part of the same.

25 In the drawing,

The figure is a perspective view of the interior of a grain separator embodying the present invention.

Referring to the drawing A represents a 30 grain separator comprising the casing 10, housing a cylinder 11 at the front end thereof and provided with a plurality of inclined decks 12 arranged in stepped relation and extending rearwardly from the cylinder to 35 the back of machine, the several parts enumerated being of any usual construction well known in the art it is deemed unnecessary to further describe the same.

Located below the cylinder is a shoe 13 40 carrying a grain pan screen 14 provided with a plurality of orifices 15 therethrough, while below the said screen is a plate 17 operatively mounted on the shoe 13 and inclined toward the rear end of the machine, 45 forming with the screen 14 a substantially acute angle.

The space between the screen 14 and the plate 17 is closed by a door 18 slidably mounted adjacent to the rear of the shoe 13 50 which supports a spout 19 extending transversely across the machine adjacent to the said door so that the wild grain is delivered from the plate 17 thereto, and thence to the side of the machine where it may be conveniently bagged. A plurality of sieves 55 20 are mounted at the rear end of the ma-

chine, and operatively connected to the shoe 13, and the tame grain after passing over the screen 14 is delivered to the said sieves.

The shoe 13 and the sieves 20 are oscillated in any convenient manner such as by the links 25 and 26 operatively connected to the crank 27 on the end of the crank shaft 28, or by any other suitable mechanism usually utilized on the grain separators at present in use, etc.

After the grain has passed through the cylinder 11 the headed grain and straw is delivered to the decks 12 and on the passage of the said straw thereover the grain 70 falls upon the screen 14 which as has been said above is subject to an oscillating motion.

The grain travels toward the rear of the screen 14 and the wild grain falls through 75 the orifices 15 and is delivered to the plate 17, located there below, from whence it is discharged into the spout 19, the tame grain passing over the sieves 20 and being thoroughly cleaned from chaff by the action of 80 the fan 21 which chaff and other roughage is delivered to the spout 22, while the good grain is delivered to the spout 23.

In cleaning flax the door 18 is closed and as the threshed flax passes over the screen 14, 85 the wild and the tame grain will pass through the orifices 15 and fill the space between the said screen and the plate 17. This will then permit of the threshed flax, including the wild and tame grain passing 90 directly over onto the sieves 20, and the wild grain there coming under the influence of the fan 21 is delivered to the spout 22 while the tame grain is delivered to the spout 23 from which it is discharged and bagged. 95

By utilizing the door 18, it will be clear that the screen 14, may be caused to perform the function of a solid plate so that it is quite unnecessary to change this screen when flax is being threshed.

That portion of the flax which lodges between the screen 14 and the plate 17 is effectively cleaned out by opening the door 18, when the said grain will be delivered to the spout and then discharged to the side of the 105 machine.

As many changes could be made in the above construction and many apparently widely different embodiments of my invention constructed, within the scope of the 110 claims, without departing from the spirit or scope thereof, it is intended that all matter

contained in the accompanying specification and drawing shall be interpreted as illustrative and not in a limiting sense.

What I claim as my invention is:

- 5 1. A grain pan screen comprising a shoe, an angularly disposed grain screen operatively mounted in the said shoe, a plate carried by the shoe located below the screen and forming therewith a substantially acute angle, means for closing the space between the said screen and plate and separating sieves adapted to receive the grain from said screen.
- 10 2. A grain pan comprising a grain screen, a shoe operatively supporting the said

screen, a plate carried by the shoe located 15 below the said screen and forming a substantially acute angle therewith, a sliding door at the rear end of the shoe inclosing the space between the screen and the said plate, and a transversely extending spout 20 adjacent to the said door.

In witness whereof I have hereunto set my hand in the presence of two witnesses.

DAVID AMBLER.
